Patented Jan. 16, 1917.

Inventor:

Charles E. McAdow.

By Jas. H. Griffin
Attorney.

UNITED STATES PATENT OFFICE.

CHARLES E. McADOW, OF JERSEY CITY, NEW JERSEY.

DESIGN FOR A CASING FOR COMBINED VENDING AND WEIGHING MACHINES.

50,205.

Specification for Design.

Patented Jan. 16, 1917.

Application filed October 2, 1916. Serial No. 123,454. Term of patent 7 years.

To all whom it may concern:

Be it known that I, CHARLES E. McAdow, a citizen of the United States, residing at Jersey City, in the county of Hudson and State of New Jersey, have invented a new, original, and ornamental Design for Casings for Combined Vending and Weighing Machines, of which the following is a specification, reference being had to the accompanying drawing, forming part thereof.

The figure is a front elevation of a casing

for combined vending and weighing machines, showing my new design.

I claim:

The ornamental design for a casing for combined vending and weighing machines, as shown.

CHARLES E. McADOW.

Witnesses:

JOSEPH I. CARROLL,
A. HORST.
